UNDERWOOD COMPUTING MACHINE COMPANY, OF NEW YORK, N. Y., A CORPORATION
OF NEW YORK.

ATTACHMENT FOR CALCULATING-MACHINES.

1,228,404.

Specification of Letters Patent.

Patented June 5, 1917.

Application filed November 26, 1910. Serial No. 594,255.

To all whom it may concern:

Be it known that I, SAMUEL E. CARLIN, a citizen of the United States, residing at Chicago, in the county of Cook and State of Illinois, have invented certain new and useful Improvements in Attachments for Calculating-Machines, of which the following is a specification.

In my application for United States Letters Patent Serial No. 547,300, filed March 4, 1910, there is shown and described an improved calculating attachment for typewriting machines embodying registering mechanism comprising registers or totalizers and traveling actuating means therefor, which actuating means is adapted to be moved into and out of operating position with relation to the register, and in a direction transverse to the axis of the operating mechanism and to be advanced to change its denominational relation to the number bearing wheels or members of the totalizer.

It has been found in practice that as the traveling actuating mechanism is advanced to change its denominational relation to the number bearing wheels or members of the totalizer, it does not accurately position itself with respect to the operating wheels of the number bearing members. It is one of the objects of the present invention to provide an improved attachment for calculating machines having means for accurately positioning the traveling actuating mechanism with respect to the operating gears of the totalizer and for holding the actuating mechanism in this position during the operation of the number bearing members of the totalizer.

A further object is to provide an improved device of this character which will be simple, durable and cheap in construction, and effective and efficient in operation.

To the attainment of these ends and the accomplishment of other new and useful objects, as will appear, the invention consists in the features of novelty in the construction, combination and arrangement of the several parts hereinafter more fully described and claimed and shown in the accompanying drawings illustrating an embodiment of the invention, and in which—

Figure 1 is a detail sectional view taken on line 1—1 of Fig. 2.

Fig. 2 is a detail top plan view of Fig. 1.

Fig. 3 is a detail perspective view of a portion of this improved attachment.

Referring more particularly to the drawings and to the present exemplification of the invention shown herein, the numeral 10 designates a support for holding the totalizer in position, said totalizer being designated generally by the reference numeral 11. The totalizer comprises the number bearing members 12 to each of which is secured a gear 13, and an operating gear 14 is provided for each of the gears 13 and meshes therewith. The gears 14 are provided with the star wheels 15 with which the retaining dogs 16 coöperate. The traveling actuating mechanism is designated generally by the reference numeral 17 and embodies a gear 18 which is adapted to be successively brought into mesh with the gears 14 as the actuating mechanism advances. Motion is imparted to the gear 18 from a gear 19 and this gear 19 is in turn operated by means of the gear 20. The gears 19 and 20 are mounted on a shaft 21 for rotation therewith and this shaft 21 is journaled in suitable bearings 22 on the carriage 23. The carriage 23 moves between guides 24 on the base 25 of the machine. This carriage is adapted to be advanced by the advancing movement of the typewriter carriage through the medium of an arm 26 which is pivotally supported as at 27. One end of the arm 26 is operatively connected to the typewriter carriage and the other end has an operating connection with the carriage 23 by means of a rack 28 connected with the carriage 23 and a segment 29 on the arm 26 in a manner similar to the manner shown and described in the above referred to application, but as this feature forms no part of the present invention further specific illustration and description thereof are not necessary.

The traveling actuating mechanism 17 is pivotally supported on the shaft 21 and is adapted to be adjusted so as to move the gear 18 out of operating position with respect to the gears 14 and in a direction transverse to the axis of the operating mechanism by means of a rock shaft 30, to which is connected an arm 31 having connection with the traveling actuating mechanism by means of the connecting members 32, 33. This rock shaft 30 is rocked by means of an arm 34 to which is connected a link 35,

The gear 20 receives its motion from a corrugated or toothed drum or cylinder 36 mounted on a running shaft 37. This drum or cylinder 36 is of some length so as to permit the traveling actuating mechanism 17 to be advanced while the gear 20 still remains in mesh therewith. All of the above described mechanism, however, forms no part of the present invention and constitutes a portion of the subject matter of the application above referred to. The operation of the mechanism thus far described, briefly stated, is as follows: Assuming the shaft 37 to be running, the drum 36 will also be running and as the gear 20 meshes therewith rotary motion will be imparted to the shaft 21. This shaft in turn will impart a rotary motion to the gear 19 which operates the gear 18 and this gear in turn actuates the opposite operating gear 14 of the totalizer. The traveling actuating mechanism is adapted to be moved out of operative position in a direction transverse to the axis of the gear 18 by means of the rock shaft 30 and when this gear 18 is thus moved into an inoperative position with respect to the gear 14, the carriage 23 and consequently the traveling actuating mechanism designated generally by the reference numeral 17 will advance to change its denominational relation to the number bearing members or wheels of the totalizer 11. After the traveling actuating mechanism has moved one step of advancement, the rock shaft 30 will operate to bring the gear 18 into mesh with the next gear 14. This operation will be continued until the gear 18 has traveled the length of the totalizer at which time the traveling actuating mechanism will be automatically returned to its starting position in the manner as set forth in the application above referred to.

During this advancement of the traveling actuating mechanism, and in practice, it has been found that the gear 18 does not always accurately mesh with the gears 14, and, for this reason, the attachment forming the subject matter of the present application is applied. Any suitable means may be provided for causing the gear 18 to be properly positioned to mesh with the gears 14 successively but a suitable and efficient mechanism for accomplishing this result will now be described.

Mounted upon the frame of the totalizer 11 is a support 38 which may be of any suitable construction but is preferably in the form of a bracket, which projects beyond the totalizer frame and mounted upon and supported by this bracket 38 is a rack 39 which may be constructed either independently of the bracket 38 and secured thereto by means of suitable fastening devices 40 as shown, or may be formed integrally therewith. This rack 39 is preferably in the form

of what might be termed a "comb" comprising teeth 41 which are spaced from each other laterally so as to form intervening spaces 42. The free extremities of the teeth 41 are pointed or reduced as shown to form beveled faces 43, the adjacent faces 43 of adjacent teeth 41 converging from the free extremities of the respective teeth inwardly toward the recesses 42, thereby forming enlarged entrance openings to the recesses having beveled or inclined faces 43.

The bracket 38 and teeth 41 are stationary with respect to the traveling actuating mechanism and co-operating with the teeth 41 is an arm or bracket 44, which is supported by and movable with the traveling actuating mechanism 17. This arm or bracket 44 is provided with a laterally projecting portion 45 having a reduced extremity 46, which extremity 46 is adapted to enter the recesses 42 in the member 39 and is of a width to substantially fill the recesses. The laterally projecting portion 45 of the arm 44 is of such a length that when the traveling actuating mechanism is shifted so as to move the operating gear 18 into an inoperative position with respect to the gears 14, to permit the actuating mechanism to be advanced, the extremity 46 thereof will be moved out of the recess 42 and clear of the extremities of the teeth 41. When the traveling actuating mechanism 17 is shifted to move the gear 18 into mesh with one of the gears 14, the reduced extremity 46 of the lateral projection 45 on the arm 44 will enter the adjacent recess 42.

It will be manifest that with this improved attachment, and in the event that the traveling actuating mechanism has not advanced sufficiently to properly position the gear 18 so as to mesh with the gear 14, or has advanced too far, the extremity 46 of the lateral projection 45 on the arm 44, when the actuating mechanism is shifted in a direction transverse to the axis of the gear 18, to move the latter into mesh with the gear 14, will engage one or the other of the beveled or inclined faces 43 of the recess 42, so as to shift the traveling actuating mechanism 17 in one direction or the other so that the extremity 46 will enter the recess 42. When the parts are in this position it will be apparent that the traveling actuating mechanism will be locked against advancement and cannot be advanced until the extremity 46 of the arm 44 is withdrawn from the recess 42.

While in the present exemplification of the invention this attachment is shown as being located above the traveling actuating mechanism, it is to be understood that it will be located in any convenient position so that it will operate to cause the proper register of the gear 18 of the traveling actuating mechanism with the respective gears 14.

What is claimed as new is—

1. The combination with a register, of actuating mechanism for said register, said register and said actuating mechanism having a relative movement past each other, so as to bring said actuating mechanism successively into coöperation with individual parts of said register, and also having a relative movement toward and from each other,
- 10 to connect and disconnect them operatively, means for bringing said actuating means and said register into approximate coöoperative relation, and justifying means for bringing said register and said actuating mechanism into accurate coöperation with each other; said justifying means acting to lock said register and said actuating mechanism against a relative movement past each other until they have had a relative movement away from each other.

2. The combination with a register, of actuating mechanism for said register, said register and said actuating mechanism having a relative movement past each other, so as to bring said actuating mechanism successively into coöperation with individual parts of said register, and also having a relative movement toward and from each other to connect and disconnect them operatively, and justifying means, carried by said actuating mechanism and said register brought into play by the relative movement of said register and said actuating mechanism, for bringing said register and said actuating mechanism into accurate register with each other.

3. The combination with a register, of actuating mechanism for said register, said register and said actuating mechanism having a relative movement past each other, so as to bring said actuating mechanism successively into coöperation with individual parts of said register, and also having a relative movement toward and from each other, to connect and disconnect them operatively, means for bringing said actuating means and said register into approximate coöoperative relation, and justifying means, mounted partly on said register and partly on said actuating mechanism, for bringing said register and said actuating mechanism into accurate coöperation with each other, the relative movement of said register and said actuating mechanism in one direction controlling their relative movement in another direction through the intermediary of said justifying means.

4. The combination with a register including a series of computing wheels, of an actuating mechanism for said register, said actuating mechanism and said register having a relative traveling movement to enable said actuating mechanism to drive said computing wheels *seriatim*, and a relative movement to cause engagement of said register

and actuating mechanism and justifying means for justifying said actuating mechanism with respect to the particular computing wheel which it is to drive at the instant of meshing of the actuating mechanism with said computing wheel, said justifying means acting to lock said register and said actuating mechanism against a relative movement past each other during the period of meshing; said justifying means including normally disengaged parts, one on the framework and the other on the relatively traveling member; and provision being made to cause the justifying parts to come into locking engagement at the relative movement between said actuating mechanism and said register, which causes engagement between said register and actuating mechanism.

5. The combination with a series of computing wheels, of a master wheel for driving said computing wheels *seriatim*, said master wheel and computing wheels having a relative movement past each other, and having a relative movement to cause engagement of said master wheel and computing wheels and justifying means for bringing said master wheel into perfect register with each computing wheel at the instant of meshing of the master wheel with each computing wheel, said justifying means acting to lock said computing wheels and said master wheel against a relative movement past each other during the period of meshing; said justifying means including normally disengaged parts, one on the framework and the other on the relatively traveling member; and provision being made to cause the justifying parts to come into locking engagement at the relative movement between said master wheel and said computing wheels, which causes engagement between said master wheel and computing wheels.

6. The combination with a series of computing wheels, of a master wheel for driving said computing wheels *seriatim*, said computing wheels and said master wheel having a relative movement transverse to the axes of rotation thereof, and justifying means brought in play by said relative transverse movement for causing an accurate registering of the master wheel with each computing wheel as it meshes to drive the same.

7. The combination with two primary elements, to wit, a series of computing wheels and a master wheel for driving said computing wheels *seriatim*, of justifying means for accurately registering said master wheel with each computing wheel as it meshes to drive the same, said justifying means including a rack connected to one of said elements and the teeth thereof being beveled at their extremities, and an arm having a reduced portion to engage the bevels of said teeth and settle between straight portions of said teeth, said arm having beveled faces at

the roots of said reduced portion to engage the beveled ends of said teeth and accurately determine the relative position of said master wheel with respect to one of said computing wheels.

8. The combination with a series of computing wheels, of a master wheel for driving said computing wheels *seriatim*, a frame for swinging said master wheel bodily to and from said computing wheels so as to engage and disengage said master wheel with respect to said computing wheels, a rack connected to said computing wheels and having guiding teeth spaced to correspond to the several computing wheels, and an arm secured to said swinging frame, having a guiding portion to engage between the teeth of said rack as said frame swings to move the master wheel into engagement with each of said computing wheels, so as to justify the position of said master wheel with the engaging computing wheel.

9. The combination with a register having a frame, of a master wheel for driving said register having a frame, a rack rigid with one of said frames, and a finger rigid with the other of said frames and in spaced relation to said rack, said frames having a relative approaching and receding movement to bring about the concomitant meshing of said master wheel to drive said register and said rack and said finger to lock said register and said master wheel against a relative traveling movement while said master wheel is driving said register.

In testimony whereof I have signed my name to this specification, in the presence of two subscribing witnesses, on this 22nd day of November, A. D. 1910.

SAMUEL E. CARLIN.
